UNITED STATES PATENT OFFICE

MOLDEN W. RIGHTEYER, OF TOLEDO, OHIO, ASSIGNOR TO THE AMERICAN SWISS COMPANY, OF TOLEDO, OHIO, A CORPORATION OF OHIO

DOORLATCH

Application filed February 20, 1932. Serial No. 594,171.

This invention relates to door latches, but more particularly to a vehicle door latch of the type in which movement of the inside handle in a non-bolt-retracting direction 5 operates to render the outside handle inoperative.

An object of this invention is to produce a vehicle door latch which is simple in construction, has a relatively small number of 10 parts, is rugged and sturdy, and is adapted to be commercially manufactured at a relatively low cost.

Another object of the invention is to produce a vehicle door latch in which a rotary 15 handle is provided for the inside of the door, and is arranged vertically from the latch unit.

Other objects and advantages of the invention will hereinafter appear, and, for 20 purposes of illustration, but not of limitation, embodiments of the invention are shown on the accompanying drawings, in which:

Figure 1 is a side elevation of a latch in 25 which the inside operating handle may be positioned at a point directly above the latch unit, and in which the latch bolt is retracted from the inside through a rack and pinion connection, which also operates upon reverse 30 movement of the inside handle to dog the outside roll back; and.

Figure 2 is a side elevation of an alternate 35 form in which inter-engaging members operate from the inside of the door for re-tracting the bolt and dogging the outside roll back.

The illustrated embodiment of the invention shown in Figure 1 comprises an elongate back plate 10 arranged in upright position and having a flange 11 at one side through which the nose 12 of a latch bolt 13 is guided. A spiral spring 14 engages a lug 15 struck out of the bolt 13, and serves to urge the bolt to latching position. The 40 movement of the bolt is guided by opposed lugs 16 integral with and extending outwardly from the back plate 10. A rivet 17 is mounted on the back plate 10 and extends through an elongate slot 18 in the bolt for 45 assisting in guiding the movements thereof.

Integral with the bolt 13 is an extension 19 with which a roll back arm 20 is engageable for retracting the latch bolt from the outside of the door. The roll back is fixed to a bushing 21, which is journaled respectively in a cover plate 22 and the back plate 10. A squared opening 23 is formed in the bushing 21 to receive an actuating spindle, on the outer end of which is mounted the usual handle.

In order to retract the latch bolt 13 from the inside of the door, an arm 24 is pivoted at one end on a rivet 25 mounted on the back plate 10, and is provided with an inclined bolt engaging surface 26 at the lower 45 end thereof. Extending inwardly toward the back plate 10 is a lug 27, with which the surface 26 of the arm 24 engages. It will be apparent that upon counter clockwise movement of the arm 24 the surface 26 50 slides over the abutment 27, and thereby causes retraction of the bolt 13 against the force of the spring 14. Formed on the arm 24 in opposed relation to the bolt engaging surface 26 is a lug or abutment 28, which 55 is adapted to be swung into the path of movement of the roll back 20. A lug or abutment 29 is integral with the roll back 20, and the lug 28 is adapted to be swung to a position at one side of the lug 29 to 60 prevent clockwise or retracting movement of the roll back.

Formed on one side of the arm 24 adjacent its pivotal mounting are teeth 30 with which teeth 31 of a rack bar 32 mesh. It 65 will be observed that the teeth 30 are in this instance arranged on the same side of the arm 24 as the bolt engaging surface 26. The rack bar 32 is guided for up and down movements on the back plate 10 by guide straps 33 and opposed vertically spaced lugs 34 integral with the back plate. Teeth 35 are formed in the opposite end of the rack bar 32 in opposed relation with the teeth 31. Meshing with the teeth 35 are teeth 36 of a 70 rotatable remote control member 37, which is supported between a cover plate 38 and the back plate. A leaf spring 39 has one end anchored in the cover plate 38, and the 75 opposite end portion is engageable in a 100

notch 40 or 41, and is adapted to ride over a surface 42. When in the notch 40 the arm 24 is held against the abutment 27 with the bolt in latching position. Movement of the 5 actuating member 37 in a clockwise direction causes the end portion of the spring to travel over the surface 42, but when the spring is in the notch 37 the arm 24 will have been moved to the left into position to dog the 10 roll back 20. A spindle 43, which is of square cross-section, is adapted to actuate the plate member 37, it being understood that a handle is mounted on the other end of the spindle.

15 In operation, it will be understood that when the actuating plate 37 is rotated in a clockwise direction the rack bar 32 is moved upwardly, and the arm 24 is rocked to the right to retract or roll back the bolt 13. 20 When it is desired to render the outside handle operative, the actuating plate 37 is rocked in a counter clockwise direction, moving the rack bar 32 downwardly and swinging the arm 24 to the left so that the 25 abutment 28 is adjacent the lug 29, thereby blocking movement of the roll back 20. Manifestly, this construction enables the inside handle to be positioned above or below the latch unit, which is found desirable in 30 some makes of automobiles since the handle on the inside of the door is arranged more conveniently for operation.

Movement of the latch bolt 13 may be prevented by a rotatable member 44 having a 35 curved surface 45 adapted to extend into a recess 46 in the latch bolt. When in the position shown in Figure 1, movement of the bolt in either direction is prevented. This member may be mounted in a housing 46, 40 and may be actuated in any suitable manner, such as by key controlled means (not shown). Obviously, rocking movement of the member 44 to the right moves the blocking surface 45 out of the recess 46, and enables movement of the latch bolt.

The latch shown in Figure 2 is similar to that above described, except that the arm 24^a is only provided with two teeth, which mesh directly with an actuating plate 37^a. 50 The actuating plate 37^a is mounted on the back plate 10^a in the same manner as the member 37 shown in Fig. 1. The remaining construction of the operative parts of the latch is identical with that above described, 55 and further description thereof is deemed unnecessary. It is apparent that rocking movement of the actuating plate 37^a in a clockwise direction operates to retract the latch bolt, and movement in the opposite 60 direction operates to dog the outside roll back.

While I have described my latch construction in more or less detail to comply with the requirements of the statute, it is, nevertheless, desired that this detailed description

be considered merely as illustrative, and not as limiting, and it is to be understood that changes in modifications may be made by those skilled in this art without departing from the invention as defined in the appended claims. 70

What is claimed is:

1. A door latch comprising a supporting plate, a spring-tensioned latch bolt movable over said plate, a roll back operable from the outside of the door for retracting said bolt, means for retracting said bolt from the inside of the door, said inside retracting means comprising inter-engaging toothed elements, means for operating said elements, means for pivotally mounting one of said elements on said plate, an arm on said last element engageable with said bolt for retracting same, and an abutment on said arm movable into the path of movement of said roll back upon a supplemental reverse movement of said inside operating means. 80

2. A door latch comprising a supporting plate, a spring-tensioned latch bolt movable over said plate, a roll back operable from the outside of the door for retracting said bolt, means for retracting said bolt from the inside of the door, said inside-retracting means comprising a pair of rotary elements, means providing a toothed operating connection between said elements, means for manually actuating one of said elements, an arm on the other element engageable with said latch bolt for retracting same, and an abutment on said arm movable into the path of movement of said roll back for preventing operative movement thereof upon a supplemental reverse movement of said actuating means. 90

3. A door latch comprising a supporting plate, a spring tensioned latch bolt movable over said plate, a roll back operable from the outside of the door for retracting said bolt, means for retracting said bolt from the inside of the door, said inside-retracting means comprising a pair of rotary elements, means providing a positive operating connection between said elements, means for manually actuating one of said elements, an arm on the other element engageable with 100 said latch bolt for retracting same, and an abutment on said arm movable into the path of movement of said roll back for preventing operative movement thereof upon a supplemental reverse movement of said actuating means. 110

4. A door latch comprising a supporting plate, a spring-tensioned latch bolt on said plate, a roll back operable from the outside of the door for retracting said bolt, a lever pivoted on said plate at one end, an abutment on said bolt with which the free end of said lever is engageable for retracting said bolt, an abutment on said lever opposed to the bolt-engaging surface and mov- 120

- able into the path of movement of said roll back for preventing operative movement thereof, and means including interengaging toothed members for rocking said lever in 5 one direction to retract said bolt or in the opposite direction to dog said roll back.
5. A door latch comprising a supporting plate, a spring-tensioned latch bolt on said plate, a roll back operable from the outside 10 of the door for retracting said bolt, a lever pivoted on said plate at one end, an abutment on said bolt with which the free end of said lever is engageable for retracting said bolt, an abutment on said lever opposed to the bolt-engaging surface and movable 15 into the path of movement of said roll back for preventing operative movement thereof, and means including a rotatable toothed operating member for rocking said lever in 20 one direction to retract said bolt or in the opposite direction to dog said roll back.
6. A door latch comprising a supporting plate, a spring-tensioned latch bolt on said plate, a roll back operable from the outside 25 of the door for retracting said bolt, a lever pivoted on said plate at one end, an abutment on said bolt with which the free end of said lever is engageable for retracting said bolt, an abutment on said lever opposed to the bolt-engaging surface and movable 30 into the path of movement of said roll back for preventing operative movement thereof, means spaced from said bolt for retracting same from the inside of the door, 35 said means including a rack and pinion connection with said lever.
7. A door latch comprising a supporting plate, a spring-tensioned latch bolt on said plate, a roll back operable from the outside 40 of the door for retracting said bolt, a lever pivoted on said plate at one end, an abutment on said bolt with which the free end of said lever is engageable for retracting said bolt, an abutment on said lever opposed 45 to the bolt-engaging surface and movable into the path of movement of said roll back for preventing operative movement thereof, teeth on said lever adjacent the pivoted mounting thereof, a vertically disposed rack 50 meshing with said teeth, means for guiding the movements of said rack, a rotatable actuating member having teeth meshing with said rack, and means for operating said rotatable member.
- 55 8. A door latch comprising a back plate, a spring-tensioned latch bolt on said back plate horizontally movable forwardly to latching position and rearwardly to unlatching position and having an upwardly extending operating portion, an outside-operated roll back pivoted on said back plate above said bolt and having an abutment extending upward from its pivot and engageable with said bolt portion, a blocking abutment extending downward from said pivot,
- an operating member pivoted on said back plate to the rear of said roll back, an arm projecting downwardly from said member and in position to contact and retract said bolt when said member is oscillated to move 70 said arm to the rearward, a hook on said member below and in front of its pivot and in position to engage said blocking abutment and prevent retracting movement of said roll back when said member is oscillated in the direction to raise said hook, an inside operable device pivoted substantially vertically above said member, and means movable in a direction substantially perpendicular to the line of movement of the bolt for connecting said pivoted device and said member for positively oscillating said member in either direction when said device is oscillated in the opposite direction.
- In testimony whereof I have hereunto 85 signed my name to this specification.
